UNITED STATES PATENT OFFICE

EMIL UMBRICK, OF JACKSON, MICHIGAN, ASSIGNOR, BY MESNE ASSIGNMENTS, TO THE COMMONWEALTH & SOUTHERN CORPORATION OF MARYLAND, OF BALTIMORE, MARYLAND, A CORPORATION OF MARYLAND

BASKET TYPE ANCHOR

Application filed March 16, 1931. Serial No. 522,900.

This invention relates to a basket type anchor. It is concerned particularly with an anchor or footing structure advantageous for use in a subsurface manner for structural elements which may be in the nature of towers.

More specifically, the invention is concerned with the provision of an anchor useful for towers of high tension power lines, but 10 it is to be appreciated that the invention may be used as an anchor or foundation member for any kind of structure other than these particular towers.

One of the objects of the invention is the 15 provision of a structure fabricated of structural iron or steel wherein the parts are arranged and related so as to minimize the number of bends in the structure, thus facilitating not only the manufacturing end but 20 also facilitating the assembly operation. Also the arrangement is such that the forces are communicated from one element to another generally in straight lines so that no objectionable stress or strain falls on bend 25 formations. Other objects and advantages of the invention will appear in the following detailed description.

Fig. 1 is a side elevational view of the assembled anchor.

30 Fig. 2 is a side elevational view looking at right angles to that of Fig. 1.

Fig. 3 is a top plane view.

Fig. 4 is an isometric view in illustration of the pyramid formation at the top of the 35 anchor member with one part cut away and shown in section.

Fig. 5 is a somewhat diagrammatic view illustrating the pyramid arrangement.

Fig. 6 is a view showing separately the 40 several members from which the basket structure may be fabricated.

First, referring to Fig. 6, it will be noted that there is an angle member 1, and an angle member 2. These two pieces may be utilized 45 for forming the base of the anchor; as shown in Fig. 3 the two members 1 may be reversed as regards each other to form two sides of the base referenced 1 and 1a. Two other sides of the base are provided by two angle 50 members 2, referenced 2 and 2a. The pyra-

mid formation is provided by four legs or risers, one rising from each corner of the base. While there are four of such risers, only three different structures need be provided as two may be identical. One of these legs is shown at 3, (Fig. 6) and in the basket structure two of these may be used; another is shown at 4, and a third at 5. Note that the members 3 and 5 are straight and provided with no bends, and that the only 60 bend in these riser members is in the member 5 having one end as at 6 bent at an angle.

These four legs or risers come together in pyramid formation as illustrated in Fig. 4, and then mounted thereon is what may be 65 termed a shoe 7, angular in cross section and bent to provide an angular part 8. Due to the fact that the legs or risers are of pyramid formation complications arise in attaching them to the base members 1 and 2. This has 70 been accomplished without providing any bends or angles in the metal other than the bend in the leg 5 and the bend in the shoe 7. This has been effected by tipping some 75 of the base members, as shown in Figs. 1 and 2.

The angle end 6 of member 5 is secured in one corner of the base, as shown in Fig. 1, and this may be accomplished by suitable bolts or rivets for which purpose member 80 5 has holes 10, and the members 1 and 2 have holes 11 and 12. Thus the angled end of member 5 constitutes a connecting element for the members 1a and 2a where they 85 meet to form a corner of the base, as shown in Fig. 3. The member 5 extends upwardly and angularly from its point of connection.

The member 4 is provided with bolt holes or rivet holes 13 and this member is bolted or riveted at the corner formed by the base 90 members 1 and 2 and it extends upwardly and angularly from the base although the angle is preferably not as great as that of member 5. Member 4 also constitutes a connecting element between base members 1 and 2.

The two members 3 connect to the other two corners of the base. One leg of the angle member 3 may be cut short as at 15 leaving the other leg extended as at 16. 100

Angle clips 17 are preferably used at the corners from which the members 3 rise. As shown in Figs. 1 and 3, one leg of one angle clip is secured to member 2a; the extended leg part 16 of a member 3 is connected to member 1 as by means of bolts, rivets, or the like taken through the member 1 and one leg of the angle clip 17, and the extension 16 as illustrated at 18, Fig. 2. The opposite corner where the angle clip is used is of the same construction and the above description of one will suffice for both.

These four legs or risers are in pyramid formation, and meet in an apex at their upper ends, details of which will be presently described. Accordingly, they all extend angularly inwardly and upwardly from the base. This requires some arrangement for accommodating for these angles. This is accomplished by positioning some or all of the base members in an angular position so that where the base members are right angle in cross section, one leg is at an angle to the vertical and one is at an angle to the horizontal. The base member 1 as shown in Fig. 3 is disposed at an angle and its upwardly extending leg is positioned so as to lie substantially flush with the legs of the angle members 4 and 3 to which it is secured. Note that members 4 and 3 approach the member 1 at very similar angles. Also by reference to Fig. 3 it will be noted that the base member 2 is connected to the member 4 and the other member 3 and that this member likewise is angularly disposed when its upwardly extending leg is bolted or riveted tight against the angle members 3 and 4.

By noting Fig. 2 it will be observed that the angle at which member 3 approaches base member 2a is such that it is preferable that the angle clips be used at these corners instead of disposing the member 2a at such a great angle. Accordingly, the base member 2a is not angled to fit member 3; similarly the base member 1a is not angled to fit the other member 3. However, the bolt holes may advantageously be so located that when the members 1a and 2a are bolted or riveted to the angle clip 17 they are given an angular disposition similar to that of base members 1 and 2. The angle at which the end 6 of member 5 is bent is such as to correspond to the angular portion of base members 1a and 2a. Inasmuch as angle clips 17 are used at the corners where the members 3 rise, one leg of the members 3 may advantageously be cut short as at 15. Accordingly, with all four base members similarly angularly disposed and the bolt holes, etc., uniformly provided, the base members are interchangeable; that is to say, 2 and 2a are identical and may be used in either location and the same is true of 1 and 1a. Thus the two members 3 and the member 4 may have straight ends embody-

ing no curves or bends; the only bend necessary being that of end 6 of member 5.

These four members meet at their upper ends in pyramid formation where they support the shoe 7 which may be of angle formation. The manner in which the members are pyramided and receive the shoe, materially facilitates assembly and provides a strong connection. As shown in Fig. 3 the outside corner of member 5 is in general alignment with the outside corner of the shoe 7. The legs of the upper part 7 of the member 5 may be beveled off as at 20. Preferably both legs of the members 3 may be beveled at their upper ends as illustrated at 21. The angle member 7 fits over the member 5; one leg of a member 3 fits in between the members 5 and 7 on one side of their bend and one leg of the other member 3 fits in between members 5 and 7 on the other side of the bend as clearly shown in Fig. 5. Bolts or rivets or the like may then be taken through the holes 22 of the shoe, 23 of a member 3, and 24 of a member 5. The holes 22, 23, and 24 come into alignment. There are similar sets of holes in the other legs of these three members for similar connection. This ties these three members together. The angled part 21 of member 3 may fit on the inside of the shoe 7 as shown in Fig. 4. This is true of both members 3. Bolts or the like may then be taken through holes 25 and 26, thus establishing a further connection between the shoe and the members 3. These holes fall beyond the member 5. The legs of the member 4 may be beveled off at the upper end as at 27 and the member 4 may then be secured to both the members 3 by bolts or the like passing through apertures 28 in member 4 and 29 in one of the legs of each member 3. The shoe 7 serves to support a leg or strut 30 which may be of angle formation fitting inside the angle member 7 and bolted or riveted thereto for which purpose member 7 has suitable apertures as shown in Fig. 6.

A showing of bolts or rivets in the assembled view Fig. 4 has been purposely omitted as the use of them would not clarify the description but would in fact, render the description and disclosure more difficult; as by not showing the rivets or bolts the reference characters applied to the apertures or holes in the structural parts may be found in their relative positions. Thus the reference characters on this assembled view conforms to those of the structural parts before assembly.

This basket structure may be devised by utilizing more or less standard angle structural members, in that only a few different types of pieces need be provided. In fact, only two types of members are used for the base and three for the pyramid. Aside from this, only the shoe and two angle clips need be provided. Only two bend operations are

necessary, one in the member 5, and one in the shoe. It will be noted that the bend line of the shoe is disposed immediately above the pyramid so that a compression force is not transmitted through the bend but is transmitted substantially on a straight line. A compression force through members 3 and 4 is transmitted on a straight line to the base, with the only bend occurring in member 5 which is located in close proximity to the base. Angle members ordinarily have a little fillet on the inside of the bend as illustrated at 31, Fig. 5. In order to fit one angle member within another snugly, it is necessary to remove this fillet by chipping or the like, or grind off the outer edge of member 5. However with the present arrangement this is unnecessary by reason of the legs of the members 3 serving as fillers between angle members 5 and 7 thus to space the outside corner of member 5 from the fillet of member 7. The legs of the angle part 8 of the shoe are arranged so as to lie substantially flush with the members 3. This is afforded by the bend in the member 7 so that the legs of this member lie substantially flush against members 3 rather than member 5. When member 7 is bolted down there may be some spreading of the legs of member 7 below the bend line bringing them into substantially flush engagement with members 3.

I claim:

1. An anchor construction comprising four angle iron base members forming a rectangular base, an angle iron riser connecting two base members at one corner and extending upwardly and inwardly, said two base members being angularly disposed and bolted substantially flush with the riser, two risers of angle iron extending upwardly from two other corners of the base and bolted respectively to the same two angle members, clips at the corners of the second mentioned risers for connecting said two base members to two other base members, a fourth angle iron riser extending from the fourth corner and serving as a connection for the second mentioned base member, all of said risers extending upwardly and angularly inwardly and meeting at an apex within the area of the base but off center thereof, and a shoe for supporting a structural element attached to some of the members at the apex.

2. In a basket anchor construction, an angle iron riser, an angle iron shoe adapted for supporting a structural member fitting over said riser and having a fillet on the inside of the angle, two angle iron risers each having a leg fitting in between legs of the first mentioned riser and shoe for spacing the outside of the angle of the first mentioned riser from the fillet in the shoe, and means uniting the risers and shoe.

3. In a basket anchor construction, an angle iron riser, an angle iron shoe adapted for sup-

porting a structural member fitting over said riser and having a fillet on the inside of the angle, two angle iron risers each having a leg fitting in between legs of the first mentioned riser and shoe for spacing the outside of the angle of the first mentioned riser from the fillet in the shoe, means uniting the risers and shoe, and a fourth riser of angle iron having its legs secured respectively to the said two risers.

4. In a basket type anchor construction, four angle iron risers meeting at an apex, an angle iron shoe supported by the risers substantially at the apex, one riser being positioned within the shoe with its outside angle adjacent an inside angle of the shoe, two risers having their angles remote from the angle of the shoe and each having a leg disposed between one leg of the shoe and one leg of the first mentioned riser, and a fourth riser having its leg positioned outside other legs of the said two risers.

5. In a basket type anchor construction, a plurality of angle iron leg members in pyramid formation meeting at an apex, a single angle iron shoe having a bend line and adapted for connection to a structural member on one side of the bend line and fitting over some of the leg members at said apex on the other side of the bend line, means securing the shoe to some of said members at the apex, said shoe being positioned so the said leg members support the same substantially at the bend line whereby a compression force is communicated substantially in a straight line from the structural member to said pyramided legs.

6. A basket anchor construction comprising, base members arranged into substantially a square base formation, a riser extending upwardly from each of the four corners of the base, two opposite risers extending inwardly at substantially similar angles and at angles to a vertical plane through the corners from which said risers extend, a third riser extending inwardly at an angle, a fourth riser extending inwardly at an angle greater than that of the angle of the third member whereby all of said risers meet at an apex disposed off center of the base, means securing the risers together at the apex and means connected substantially at the apex for supporting a structural member.

7. In combination a structural member of a tower or the like disposed at an angle to the vertical, a supporting base generally of square shape disposed so that substantially the center of the base coincides with an extension of the structural member, four risers one extending upwardly from each corner of the base, two opposite risers extending upwardly and angularly at different angles whereby they meet at an apex off center as regards the base, two other risers extending upwardly from opposite corners and meet-

ing the first two risers at the apex, means connecting the structural member to the risers substantially at the apex, said risers being arranged and disposed so that the apex is positioned substantially on a diagonal line of the base and between the center of the base and one corner thereof.

8. An anchor construction comprising, structural members forming a substantially square base, a relatively short riser extending upwardly and inwardly from one corner of the base, a relatively long riser extending upwardly and inwardly from the opposite corner of the base, a pair of similar risers extending upwardly and inwardly from the other two opposite corners of the base, said risers being arranged to meet in an apex whereby said apex is positioned substantially on a diagonal line of the square base and between the center thereof and the corner of the base from which the relatively short riser extends, and means connected to the risers substantially at the apex for supporting a structural member.

9. An anchor construction comprising, structural members forming a substantially square base, a relatively short riser extending upwardly and inwardly from one corner of the base, a relatively long riser extending upwardly and inwardly from the opposite corner of the base, a pair of similar risers extending upwardly and inwardly from the other two opposite corners of the base, said risers being arranged to meet in an apex whereby said apex is positioned substantially on a diagonal line of the square base and between the center thereof and the corner of the base from which the relatively short riser extends, said risers being adapted to support a structural member from substantially the apex, which structural member is angularly disposed so that a projection of its angular extent substantially coincides with the center of the base.

45. In testimony whereof I affix my signature.
EMIL UMBRICKT.
